UNITED STATES PATENT OFFICE

ALBERT J. STEGEMAN, OF QUINCY, ILLINOIS, ASSIGNOR TO WESTINGHOUSE ELECTRIC AND MANUFACTURING COMPANY, A CORPORATION OF PENNSYLVANIA

DESIGN FOR AN ELEVATOR CAB

Application filed January 17, 1931. Serial No. 38,346. Term of patent 14 years.

To all whom it may concern:

Be it known that I, ALBERT J. STEGEMAN, a citizen of the United States, residing at Quincy, in the county of Adams and State of Illinois, have invented a new, original, and ornamental Design for an Elevator Cab, of which the following is a specification, reference being had to the accompanying drawings, constituting a part hereof:

Figures 1 and 2 are views in perspective of opposite corners, respectively, of the interior of an elevator cab,

Fig. 3 is a detail view on an enlarged scale, in perspective, of an interior upper corner of a cab, and

Fig. 4 is a view, in perspective, of an elevator cab of conventional construction, to the interior of which my design is applicable.

It is to be understood that the color of the plane wall surfaces may contrast with the color of the fluted portions as indicated in Fig. 3.

I claim:

The ornamental design for an elevator cab substantially as shown.

In testimony whereof, I have hereunto subscribed my name this 7th day of January, 1931.

ALBERT J. STEGEMAN.
